ABSTRACT

A hydraulically operated tool for cutting multi-strand cable comprises a pair of jaws mounted on a linkage to be opened and closed by a hydraulic piston and cylinder unit. To ensure effective cutting of the cable a cable grip is provided which is manually operable and comprises a pair of jaws close to the cutting jaws of the tool and movable to clamp and release a cable to be cut.

HYDRAULICALLY OPERATED HAND TOOLS

This invention is concerned with hydraulically operated hand tools of the kind having a set of jaws movable towards and away from each other.

A hand tool exemplary of the kind with which this invention is concerned, is described in U.S. Pat. No. 2,791,028 issued May 7, 1957 to Peter Bidin and while it will be apparent that this invention has other applications, it has been developed, in its several aspects, as an improvement of the Bidin tool.

In general terms the Bidin tool comprises a pair of handles, a pump operated by one of the handles and adapted to operate a ram on the housing on which the handles are mounted. The ram actuates, through an appropriate linkage, a pair of cutting jaws.

A difficulty of tools of the Bidin type has been that they cannot effectively be used for cutting multi-stranded cable for the jaws have tended to follow the lay of the strands of the cable or the cable has moved within the jaws because of the lay of the strands of the cable.

To overcome this disadvantage there is provided, according to another aspect of this invention, a hydraulically operated hand tool for cutting cable having a manually operated cable grip arranged to grip cable adjacent to the cutting jaws of the tool said grip comprising a pair of gripper jaws each having a cable gripping surface, and an operating mechanism for moving the gripper jaws between open and closed positions.

It is desirable that the cable gripping surfaces be formed on parts which are separable from the jaws themselves and to this end they may be in the form of blocks mounted upon the jaws and having part-circular sectioned gripping surfaces. To render the blocks suitable for different sizes of cable it is desirable to form the blocks with several differently sized semi-circular sectioned grooves and for the blocks to be rotatable to bring one or the other of the grooves into an operative position.

It will be appreciated that by having the cable grip operating mechanism manually operated the cable can be engaged by the cable grip prior to the cutting operation rather than relying on the cutting action to bring cable grips into operation.

An embodiment of this invention is illustrated in the accompanying drawings in which,

FIG. 1 is a front view, partly in section, of a tool according to this invention, especially adapted for cutting multi-strand cable,

FIG. 2 is a detail of the embodiment of FIG. 1, partly in section and in which certain parts are removed in the interest of clarity,

FIG. 3 is a cross-sectional view through the lower end of the ram cylinder and the pump of the tool taken on the line 3-3 of FIG. 5.

FIG. 4 is a cross-section on the line 4-4 of FIG. 3, and

FIG. 5 is a cross-section on the line 5-5 of FIG. 4.

The tool is, in many respects, similar to the Bidin tool. It comprises a pair of handles 10 and 11 connected to a generally cylindrical casting 12 which constitutes the ram housing. At the upper end of the ram housing a jaw supporting structure 13 is mounted and this carries the cutter jaws, which are generally indicated at 14, and their associated linkage. The cable

gripping mechanism generally indicated at 15 is also carried on the supporting structure 13.

The ram housing is a generally cylindrical casting which has projecting downwardly from one side thereof, a sleeve 20 and from the opposite side thereof, an arm 21.

The sleeve 20 has an axial passage 22 which is of reduced diameter at its upper end 23 so that a shoulder 24 (FIG. 3) is formed at the transition from the larger to the smaller diameter sections of the passage. The lower edge of the sleeve has a circumferential section 25 cut away to provide, at each end of that section, a stop. The purpose of the stops is described hereinafter.

The handle 11 is accommodated in sleeve 20 and has an upper portion 30 of a slightly lesser diameter than the reduced diameter of section 23 of sleeve 20 so as to be rotatable therein. The portion 30 projects outside the sleeve 20 and is secured in position by circlip 31 located in an appropriate groove in the portion 30.

Immediately below the portion 30 and accommodated in the larger diameter section of passage 22, there is on handle 11 an eccentric section 32 which cooperates, as described hereinafter, with a push rod to allow the cutter jaw to open. Below the eccentric, the handle part 33 within the sleeve is of circular section and is provided with a radial peg 34 which projects into the cutaway section 25 of the lower edge of the sleeve and cooperates with the stops formed by that section to limit the rotary movement of the handle within the sleeve between positions corresponding to the extreme positions of the push rod controlled by eccentric section 32.

The arm 21 projecting downwardly from the side of the ram housing opposite to the sleeve 20 terminates in an eye 40 to which the handle 10 is pivoted.

The handle 10 is in the form of a bell crank of which the short arm 41 and the region of the pivot are bifurcated. The bifurcated pivot region is located over the eye 40 and the pivot pin 42 passed through the eye and corresponding holes in the handle to mount the handle for pivotal movement on the arm 21. A pin 43 extends between the bifurcated sections of the arm 41 remote from pivot pin 42 and a saddle 44, FIG. 3, connects that pin to the outer end of a piston rod of the hydraulic pump of the tool.

The lower end of the housing 12 is closed by a base 50. Screwed into an appropriately threaded opening 51 in the bottom of the base 50 is a pump cylinder 52 (FIG. 3). Within the cylinder 52 a piston 53 is slidably located and has a piston rod 54 which projects to the outside of the cylinder through a centrally apertured screw threaded piston rod guide 56. A packing element 55 is located around the piston rod to prevent leakage of fluid therewith.

The outer end of the piston rod 54 has an annular groove 58 within which the saddle 44 of the handle 10 is located. Thus it will be seen that movement back and forth of handle 10 towards handle 11 causes reciprocation of rod 54 and piston 53.

The base 50 is located in position within the housing 12 by a circlip 60 and by a radially disposed grub screw (not shown in the drawings) located in a hole in the wall of the housing 12. The ram cylinder 70 (described later) which is screw fitted into the base abuts the upper end of the housing and also serves to positively locate the base 50.

Surrounding the ram cylinder in the space between the outer surface of the ram cylinder and the inner surface of the housing 12 is a flexible and resilient bag reservoir 71, the adoption of which renders the device useful for operation in any position inasmuch as, the bag, being distendable ensures that the pump always has fluid available to it. The general principle of this flexible bag reservoir is described more particularly in Bidin's U.S. Pat. No. 2,618,929 issued Nov. 25, 1952. In that patent the reservoir is shown as a space sealed off by an annular piston which is spring urged always to maintain fluid available for the pump; however, it is to be appreciated that mechanically, the action of the flexible bag described herein is much the same as that earlier Bidin arrangement.

The bag forming the reservoir is firmly secured at its lower end 72 between the inner wall of the housing 12 and the adjacent surface of the base 50 within a groove formed around the upper and outer edge of the base. The upper end 73 of the reservoir is bonded to the outer surface of the ram cylinder.

The ram cylinder comprises a tube externally threaded at its lower end 74 for location in a correspondingly threaded central recess 75 in the upper surface of base 50 and having its upper end located in the recess 76 in the axial end closure wall 12a of the housing 12.

Slidably located within the ram cylinder is a piston 78 secured on a piston rod 79. The rod extends through a central opening in the end wall 12a of the ram housing 12 for connection, as described hereinafter, to the jaw operating linkage.

The base 50 includes the valve passages to provide fluid communication between the reservoir, the ram cylinder and the pump.

A main passageway 80 (FIG. 3) extends diametrically across the base and comprises a first section 81 of relatively large diameter, a second section 82 of smaller diameter than section 81, the shoulder of the transition between the two diameters constituting a seat 83 for the ball valve 84. There is a third section 85 of lesser diameter than the second section and a fourth section 86 of similar diameter to the second section. The fourth section registers with an opening 87 through the wall of housing 12 into the sleeve 20 for handle 11. For the purpose of assembling the tool a hole 88 is formed in the wall of sleeve 20 directly opposite to the opening 87 and after assembly that opening is plugged as at 89. The transition between the diameters of the second and third sections constitutes a seat 90 for ball valve 91.

The ball valve 84 is spring loaded by a coil spring 92 towards the seat 83 and the spring is retained by a screw 93. The screw 93 has a small spigot 94 which extends axially within the spring 92 so as to guide the spring and the ball 84 to effect a positive opening and closing action of the ball valve and thus to prevent flutter which might occur in the absence of the spigot.

Located in the second section 82 of passage 80 and between the balls 84 and 91 is a spacer piece 95 the action of which is described hereinafter.

A stem 96 is slidably located in the fourth section of the passageway 80 and extends through opening 87 into the sleeve 20 to be moved by the eccentric portion 32 of the handle 11 when that handle is turned about its own axis. The stem 96 has an annular groove within which an O-ring 97 is located, the O-ring sealing the

small space between the stem and the surface of the section 86 of passage 80.

The inner end of the stem 96 has, formed integrally therewith, a push rod 98 which projects into the section 85 of passageway 80 and is of such length that when the handle 11 is turned to move the stem inwardly, the push rod lifts the ball 91 from its seat 90 and causes that ball to push spacer piece 95 onto ball 84 and lift that ball from its seat 83 against the action of spring 92.

It will be appreciated that the opening 88 in the outer wall of sleeve 20 allows the stem 96 to be inserted. The balls 91 and 84 and the spacer piece 95 and the spring 92 are inserted from the other end of passage 80.

A bore 99 is formed between the recess at the upper end of the pump 52 and the second section 82 of the passage 80. Another bore 100 extends between the section 86 of passageway 80 and the reservoir 71. A third bore 101 communicates between the first section 81 of passageway 80 and the lower port of ram cylinder 70.

A bore 102 (seen only in FIG. 5) extends right through the base 50 to the reservoir 71 and this serves for filling or topping up the reservoir. The lower end of the bore is closed by a screw and washer.

A radial bore 103 extending normally to the passageway 80 and communicating with the second section 82 of that passage 80 is formed in the base. The innermost part 104 of bore 103 which opens into passageway 80 is of smaller diameter than the remainder of that bore and the shoulder of the transition to that smaller diameter constitutes a seat for a ball 105. The outer end of the bore is threaded to receive a screw 106, and an axial groove 107 is made in the wall of the bore. The screw 106 is grooved to receive an O-ring 106a to prevent the passage of fluid past the screw except through groove 107 which terminates inwardly of the O-ring. Between the innermost end of the screw 106 and the ball 105 are located a pair of dish-shaped springs 108 which load the ball towards its seat.

A bore 109 is made between the groove 107 and the upper surface of the base 50 in the region where that upper surface closes the reservoir 71 so that when the ball 105 is moved from its seat fluid can flow from the section 82 of the passageway 80 into the bore 103 through groove 107, into the bore 109 and into the reservoir 71.

The operation of the pump and ram is as follows: When the handle 11 is turned to the position illustrated in FIG. 3, with the push rod 98 withdrawn from the ball 91, movement of handle 10 away from the handle 11 induces the suction stroke of the pump 52. Ball 91 is lifted from its seat and fluid drawn into the pump from the reservoir through bores 100 and 99. Ball 84 is maintained on its seat by spring 92.

As the handle 10 is moved towards handle 11 fluid is pumped through bore 99 causing the ball 91 to move on to its seat and causing the ball 84 to be lifted from its seat. The fluid then flows, through bore 101, to the ram cylinder to extend the ram.

When it is desired to permit the ram to be retracted, the handle 11 is turned and the eccentric 32 causes balls 91 and 84 to be lifted from their respective seats by the push rod 98 and the spacer piece 95. Fluid can flow from the ram cylinder to the reservoir through bore 101, passage 80 and bore 100.

In the event that the pressure in the ram cylinder exceeds a safe maximum (because the material being cut is too strong or the operator continues to pump after the ram has been fully extended) pressure in section 82 of the passage 80 builds up applying a pressure on ball 105 through bore 104. The spring loading of ball 105 is set by screw 106 so that when a pressure in excess of the maximum permissible pressure exists in the cylinder, the ball 70 is lifted from its seat and fluid flows through bores 104 and 109 to the reservoir thus preventing overloading and consequent damage to the blades.

In earlier tools it was found that the cutter blades would cross before the maximum premissible pressure was reached and this effect caused damage to those blades. To overcome this disadvantage the upper end of the ram cylinder is internally threaded as at 110 to cooperate with an end closure cap 111 which is externally threaded. The inner end surface 112 (i.e. the end nearest to piston 78) presents a shoulder which acts as an abutment to limit the outward movement of the ram by coacting with the piston of the ram. A screw-threaded hole (not shown) is formed radially through the wall of the ram cylinder so that a set screw can be introduced into that hole to lock the relative positions of the cap 111 and the cylinder. The cap is so positioned that the piston and the abutment shoulder 112 come into contact just as, or slightly before, the cutter blades generally indicated at 14 are closed so that those blades cannot cross over each other or be pressed together with undue force. It will be appreciated that the cap can be adjusted to obtain this desired position.

The jaw support structure or jaw head 13 (FIG. 1) is secured to the upper end of the ram housing 12 by connector 120. The upper region of the housing 12 is externally screw threaded as at 121 and has a carefully finished annular shoulder 122 (FIG. 2). That shoulder 122 is finished to be normal to the axis of the ram.

The lower end of the support 13 is recessed as at 123 to accommodate the upper reduced diameter section of the housing and has an accurately finished annular surface 124 for cooperation with shoulder 122 of the ram housing so that when those two surfaces are brought firmly together the housing and the support are accurately aligned.

Above surface 124 a groove 125 is cut around the outside surface of the support structure to accommodate one or more spring steel split rings 126. The connector 120 is in the form of a sleeve which is internally screw threaded for cooperation with the threads 121 of the upper end of the ram housing and has at its upper edge a radially inwardly extending flange 127 which engages the split rings 126. To assemble the jaw support structure to the ram housing, the connector 120 is located on structure 13 above the groove 125 and the ring 126 is located in position. The structure 13 and housing 12 are then brought together and the connector screwed tightly on to the housing. The split rings will flex as the connector is screwed down to an extent which will allow face-to-face contact between the surfaces 122 and 124 thus accurately aligning the housing and the support structure.

The support structure is hollow and is slotted as at 130 and 131 to accommodate projecting ears 132 and 133 of a cross head 134 located within the structure.

The cross head is secured to the upper end of the ram piston rod 79. Located within the support structure and working against the action of the ram is a coil spring 135.

5 To the ears 132 and 133 a pair of links 136 and 137 are respectively pivoted on pins 138 and 139. Between the outer ends of links 136, the tail 140 of a jaw 141 is pivoted on pin 142 and similarly, between the outer ends of links 137 the tail 143 of a jaw 144 is pivoted on pin 145. These are the jaws previously mentioned as being generally indicated at 14.

The jaws 141 and 144 are pivoted to the support structure about pins 146 and 147, respectively, which extend across the gap between opposite sides of the slotted upper end 148 of the structure. Thus, movement upwardly of the cross head 134 causes the jaws to be closed and movement downwardly of that head causes the jaws to be opened.

15 20 For cutting bar or rod, the device so far described is sufficient, but to facilitate the cutting of multi-strand wire or cable it is desirable to have a cable grip. This grip comprises an operating handle 150 pivoted on a stud 151 screwed into an appropriately threaded hole

25 25 on the jaw support structure. The handle is notched at 152 to cooperate with a peg 153 to limit the movement of the handle in one, the closing, direction. The upper end of the handle has two laterally projecting arms 154 and 155, said arms being apertured to receive pivot

30 30 pins 156 and 157 respectively upon which pairs of links 158 and 159, respectively, are mounted. A pivot pin 160 connects the free ends of the pair of links 158 to a clamping or gripper jaw 161. Similarly pivot pin 162 connects the free ends of links 159 to a clamping or 35 35 gripper jaw 163. The jaws 161 and 163 are pivotally mounted on extensions of pivot pins 146 and 147, respectively, which also pivotally mount the cutting jaws of the tool.

40 40 Thus, as the handle 150 is moved to the right as viewed in FIG. 1, the gripper jaws will be opened and as it is moved, from its jaw opening position, to the left to an overcenter position abutting stud 153, the gripper jaws will be closed.

45 45 At the upper ends of clamping jaws 161 and 163 there are clamping elements 170 and 171, respectively. Elements 170 and 171 are pressed on to studs 173 and 174 projecting from their corresponding jaws and are generally block-shaped with part circular section 50 50 grooves formed in each surface parallel to the studs upon which they are mounted. The curvature of the groove in each surface of one element is different from the others of that element, but the blocks are similar so that by turning the elements about the studs upon 55 55 which they are mounted, a pair of similar grooves, one on each block, can be brought into opposition. In this way a clamp suitable for different cable diameters is provided.

60 60 It will be appreciated that the tool herein described has several advantages over prior art arrangements and particular its ability reliably to cut multi-strand cable.

What is claimed is:

1. A cable cutter tool comprising a support, a pair of cutter jaws having cutting edges and pivotally mounted 65 65 on the support for movement towards and away from each other, power means connected to the cutter jaws to move said jaws towards each other in a cutting ac-

tion, a pair of gripper jaws pivotally mounted on the support beside the cutter jaws for movement towards and away from each other, and a gripper element movably mounted on each gripper jaw, said gripper elements being mounted on the gripper jaws so that when said gripper jaws move towards each other the gripper elements move towards each other adjacent the cutting edges of the cutter jaws, each gripper element having a plurality of different cable gripping surfaces formed therein, and said elements being movable relative to each other and the gripper jaws to bring selected ones of said gripping surfaces into operative position.

2. A cutter tool as claimed in claim 1 including manually-operable means connected to the gripper jaws for moving said gripper jaws towards and away from each other.

3. A cutter tool as claimed in claim 1 in which each gripping surface of the gripper elements comprises a part circular section groove.

4. A cutter tool as claimed in claim 1 in which each gripper element comprises a block pivotally mounted on one of said gripper jaws.

5. A cutter tool as claimed in claim 1 in which said cutter jaws are pivotally mounted on pins carried by the support, and said gripper jaws also are pivotally mounted on said pins.

6. A cutter tool as claimed in claim 1 in which said gripper jaws are swingably mounted on pins carried by the support, said gripper elements being mounted on ends of the gripper jaws on one side of said pins and the

5 gripper jaws having free ends on the opposite side of said pins, and including a handle swingably mounted on a pin carried by the support between the free ends of the gripper jaws, arms on the handle near the pin thereof and extending towards said gripper jaw free ends, and links connecting the arms to said free ends whereby swinging of the handle causes the gripper jaws to swing to move the gripper elements towards and away from each other.

10 7. A tool for a cable cutter having cutter jaws, comprising a pair of gripper jaws adapted to be mounted on a cable cutter adjacent cutter jaws thereof for movement towards and away from each other, and a gripper element movably mounted on each gripper jaw, said gripper elements being mounted on the gripper jaws so that when said gripper jaws move towards each other the gripper elements move towards each other, each gripper element having a plurality of different cable gripping surfaces formed therein, and said elements 15 being movable relative to each other and the gripper jaws to bring selected ones of said gripping surfaces into operative position.

20 8. A tool as claimed in claim 7 including manually-operable means connected to the gripper jaws for moving said gripper jaws towards and away from each other.

25 9. A tool as claimed in claim 7 in which each gripper element comprises a block pivotally mounted on one of said gripper jaws.
